UNITED STATES PATENT OFFICE.

RUDOLPH C. NORBERG, OF CLEVELAND, OHIO, ASSIGNOR TO THE WILLARD STORAGE BATTERY COMPANY, OF CLEVELAND, OHIO, A CORPORATION OF OHIO.

DESIGN FOR A CONNECTOR FOR STORAGE BATTERIES.

45,348.

Specification for Design.

Patented Mar. 3, 1914.

Application filed November 14, 1913. Serial No. 801,086. Term of patent 7 years.

To all whom it may concern:

Be it known that I, RUDOLPH C. NORBERG, a subject of the King of Sweden, residing at Cleveland, in the county of Cuyahoga and State of Ohio, have invented a new, original, and ornamental Design for Connectors for Storage Batteries, of which the following is a specification, reference being had to the accompanying drawing, forming part thereof.

In the drawing, Figure 1 is a plan view; Fig. 2 is an edge view; Fig. 3 is an edge

view looking at the device from the edge opposite to that of Fig. 2, and Fig. 4 is an end view of the connector, showing my new design.

I claim:

The ornamental design for a connector for storage batteries, as shown.

RUDOLPH C. NORBERG.
